UNITED STATES PATENT OFFICE.

ROBERT LEE CAMPBELL, OF MORRISTOWN, TENNESSEE.

INDICATOR.

Application filed June 14, 1923. Serial No. 645,428.

To all whom it may concern:

Be it known that I, ROBERT L. CAMPBELL, a citizen of the United States, residing at Morristown, in the county of Hamblen and State of Tennessee, have invented new and useful Improvements in Indicators, of which the following is a specification.

This invention relates to signals or indicators and has for its object the provision of a novel device which is designed to be mounted at the door of a dwelling, office or other building and operable whereby to appraise a visitor as to whether or not the occupant is at home or away, the indication given of course depending upon the way the mechanism is set.

An important object is the provision of a device of this character which is inactive unless the visitor pushes the push button for ringing the bell and attracting the attention of the occupant.

An additional object is the provision of a device of this character which will be simple and inexpensive in manufacture and installation, efficient and durable in use and a general improvement in the art.

With the above and other objects and advantages in view the invention consists in the details of construction to be hereinafter more fully described and claimed and illustrated in the accompanying drawings, in which:

Figure 1 is a diagrammatic view of the system,

Figure 2 is a detail elevation of the indicator on a larger scale,

Figure 3 is a vertical section therethrough,

Figure 4 is a horizontal section,

Figure 5 is a detail view of the indicator member or movable element and

The remaining figures are detail views.

Referring more particularly to the drawings I make use of an indicator comprising a casing 10 provided in its front with a dial 11 bearing any desired reading matter but preferably the name of the householder, office tenant or other owner of the signal and also bearing any other matter designed to explain the action in case a visitor is not familiar with what the device is for. The dial is provided with a slot 12 for a purpose to be described. Mounted at the top of the casing 10 is a suitable bracket carrying a reflector 13 in which is held an incandescent bulb 14 which may conveniently be a flash light bulb and which is for the purpose of

illuminating the dial at night or in fact at any other time in case such is desired.

Located within the casing 10 and immediately in back of the dial is a roller 15 mounted on a spindle 16 suitably journaled and carrying a transverse needle 17 formed as a permanent magnet adapted to engage a stop bracket 18. Positioned to attract this needle is an electromagnet 19 which when energized by current flowing in one direction will attract the needle and move the roller 15 in one direction, and which when energized by current flowing in the other direction will attract the needle and move the roller in the opposite direction. When the roller is in its neutral position and held as for instance by a hair-spring or the like, not shown, the needle engages the bracket 18.

This roller carries indicia or legends applied thereto by any desired means though a convenient method is to provide a strip of paper which is secured to the roller and which bears the two legends "At home" and "Not here." Between these two legends is a blank space which is normally exposed through the slot 12 when the device is in neutral or non-signalling position. When the electromagnet is energized the needle will be attracted and the roller will be turned in one direction or the other so that the proper one of the legends will be displayed through the slot in the dial.

In connection with the above described mechanism I provide an ordinary push button 20 which is located on the door frame or any other place desired and which is intended to be pushed by a visitor to ring the bell for attracting the attention of the occupant. I also employ a conventional electric bell 21, two or more dry cells 22 and a double pole, double throw reversing switch 23. The dry battery is connected by a wire 24 with one terminal 25 of the switch, which terminal is connected with the diagonally opposite terminal 26. The other pole of the battery is connected by a wire 27 with a third terminal 28 of the switch which is in turn connected with the diagonally opposite terminal 29. The switch includes the usual blades 30 and 31 which are pivoted at 32 and 33 respectively and which are movable into engagement with the contacts 25 and 28 or 26 and 29. The pivot 32 of the switch is connected by a wire 34 with the push button and the push button is also connected by a wire 35 to one

terminal of the electric bell which has its other terminal connected by a wire 36 with the other pivot 33 of the switch. Connected with the wire 36 is a branch wire 37 which 5 is connected with the electromagnet 19 which has its other terminal connected by a wire 38 with a wire 39 which connects with the wire 35. The electric lamp has its terminals connected with the wires 37 and 39 by wires 10 40 and 41. By this diagram it will be seen that the electromagnet is in parallel with the bell and that the incandescent bulb is also in parallel therewith so that when the bell is energized by pressure upon the push 15 button 20 the lamp and electromagnet will be energized at the same time as the bell so that a signal will be given if the switch is in either one of its operative positions. If the switch is in neutral position the entire 20 system is inoperative.

In the operation it will be seen that if the switch has its blades in engagement with the contacts 25 and 28 the direction of current through the electromagnet will be opposite to the direction it would have if the blades of the switch were in engagement with the contacts 26 and 29. In fact the whole purpose of this switch is to reverse the direction of current flow. If the occupant is 25 at home he throws the switch to the proper limit of its movement whereupon when a visitor presses the push button the bell will ring, the light will light and the electromagnet will be energized to attract the needle 18 and swing the roller 15 into such 30 position that the legend "At home" will be visible through the slot 12. Upon going out it is intended that the householder throw the switch in the other direction, whereupon 35 40 when a visitor applies pressure to the push button, the circuit will be closed for ringing the bell and lighting the light but the direction of current flow through the elec-

tromagnet will be reversed which will cause the needle 18 and consequently the roller 15 45 to be moved in the opposite direction so that the legend "Not here" will be visible through the slot.

From the foregoing description and a study of the drawings it will be apparent 50 that I have thus provided a simply constructed and easily installed signalling device which will be highly efficient and convenient for the purpose specified and which will save a visitor the annoyance of repeatedly ringing a bell for quite a while and determining that the occupant is not home. 55

While I have shown and described the preferred embodiment of the invention it is of course to be understood that I reserve the 60 right to make such changes in the form, construction and arrangement of parts as will not depart from the spirit of the invention or the scope of the subjoined claim.

Having thus described my invention I 65 claim:

A signal device of the character described comprising an enclosing casing having a dial provided with a vertically elongated slot, a rectangular frame member mounted within 70 the casing at the intermediate portion thereof, a vertically arranged cylinder pivoted within said frame to the rear of said slot, a permanent magnetic needle of angular formation carried by said cylinder and having a vertical portion projecting above said frame and engageable therewith for limiting rotative movement of the cylinder in both directions, said cylinder bearing indications 75 adapted to be displayed through the slot, and an electro-magnet mounted in horizontal position within the casing in position to attract or repel said polarized permanent magnetic needle.

In testimony whereof I affix my signature.

ROBERT LEE CAMPBELL.
